H. RADZINSKY.
HAIR CURLER.
APPLICATION FILED MAR. 11, 1920.

1,338,748.

Patented May 4, 1920.

Inventor
Harry Radzinsky

UNITED STATES PATENT OFFICE.

HARRY RADZINSKY, OF NEW YORK, N. Y.

HAIR-CURLER.

1,338,748.

Specification of Letters Patent. Patented May 4, 1920.

Application filed March 11, 1920. Serial No. 365,029.

To all whom it may concern:

Be it known that I, HARRY RADZINSKY, a citizen of the United States, and a resident of the city, county, and State of New York, have invented a certain new and useful Improvement in Hair-Curlers, of which the following is a specification.

This invention relates to a hair retaining device more particularly adapted for curling or crimping the hair. The object of this invention is to provide such a hair holder or crimper, which is preferably constructed of a narrow strip of resilient material of desired length which may be folded upon itself to form two opposing arms upon which the hair is usually wound so that these two arms grip, press or clamp the hair between them, an improved means being provided for retaining the two ends of the arms together.

The two arms may, as above set forth, be formed by bending a continuous strip of flexible or resilient material transversely, or if desired the two arms may be formed by pivotally connecting two pieces of material together in a desired manner.

A further object of this invention is to provide an improved means for detachably connecting or holding the two ends of the arms together while the device is in use, such means being so constructed that inadvertent separation of the two arms is made very unlikely.

With these objects and other objects which may hereinafter appear, in view, I have devised the construction hereinafter set forth, and more particularly pointed out in the claims appended hereto.

Reference is to be had to the accompanying drawing, forming a part hereof, in which—

Figure 1 is a plan view of a hair curler in closed position, provided with my improvement;

Fig. 2 is a side view of the same in open position;

Fig. 3 is a face view of one end of the arms, showing the manner in which the locking means is produced;

Fig. 4 is a sectional view on the line 4—4 of Fig. 3, looking in the direction of the arrows;

Fig. 5 is a sectional view on the line 5—5 of Fig. 1, looking in the direction of the arrows;

Fig. 6 is a face view of one end of one

of the arms of the curler showing the manner in which a modified form of locking means is produced;

Fig. 7 is a perspective view showing the second step taken to produce the modified form of locking means from the blank shown in Fig. 6; and

Fig. 8 is a perspective view showing the modified form of locking means produced from the blank disclosed in Fig. 6.

Throughout the various views of the drawings, similar reference characters designate similar parts.

In the preferred embodiment of my invention, as illustrated in the accompanying drawing, the hair curling device is preferably produced from a single piece of flat resilient material in the form of an elongated strip, which is transversely folded upon itself to form a loop 1, and a pair of oppositely disposed, normally separated, spring arms 2 and 3. While I have shown the device formed from a single strip of material and the two arms 2 and 3 integral, it will be understood that these two arms can be formed of separate pieces of material suitably united by a pivotal means.

The arm 2 is provided with a point 4 at one of its ends and the other arm 3 is provided with a locking device to receive and retain the end of the arm 2. This locking device is in the form of a hood or shield 5 into which the arm 2 is moved. In Fig. 3 it will be seen that this shield or hood 5 is produced by means of a laterally extending portion or offset 6 on the end of the arm 3. This offset or laterally extending flange 6 is bent or folded on the line 7^a so that it overlies the end of the arm 3.

The laterally extending portion or offset 6 is provided with an elongated longitudinally extending projection or hump 7 adjacent its edge, while the opposite edge of the arm 3 is provided with a like projection or hump 8. When the offset, or laterally extending portion 6, is bent or folded upon the line 7^a it will be seen that the projections 7 and 8 contact and form a resilient and separable locking means for the end 105 of the arm 4. To close the device the arm 2 is moved laterally so that its end passes in between the projections 7 and 8, the resiliency of the material from which the device is formed permitting this. The projections hold the device in closed position at all times, yet permitting the arm 2 to

be moved in or out of the hood or shield 5 when desired. To aid in moving the arm 2 laterally to perform the opening or closing operation, this arm is provided with a 10 longitudinally extending rib 9 for engagement by the finger of the person using the device.

In Figs. 6, 7 and 8, is shown a modified 15 form of device, in which the arm 3 is provided with lateral extensions or offset flanges 10 and 11. These flanges are coiled or rolled up at their edges as at 12 and 13 (Fig. 7) and the device is then formed as shown in Fig. 8 so that the rolled-up portions 12 and 13 contact and produce the locking projections.

I have shown the locking projections of 20 the device in the form of elongated members, but it will be understood that these 25 may be varied in many particulars, and can perform the necessary functions of the device herein described.

Having described my invention, it is obvious 30 that the same is not to be restricted to 35 the exact embodiment shown, but is broad enough to cover all structures coming within the scope of the annexed claims.

Having described my invention, what I 40 claim is:

- 30 1. A hair curler having a pair of flat resilient arms, means for holding the ends of the arms together, comprising a hood, said hood being formed by a transversely bent extension of one of the arms at its end, a 35 projection formed at the edge of said transversely bent extension, and a projection on the edge of the arm below the projection on the extension, said projections contacting and resiliently closing the entrance to the 40 hood.
2. A hair curler having an arm, said arm having a closure means comprising a lateral extension bent to overlie the arm adjacent its end and coöperating with the same to 45 form a hood into which another arm is movable, means for retaining said last mentioned arm within the hood, comprising a pair of coöperating separable projections at the end of the lateral extension and on the 50 arm.
3. A hair curler having a closure means comprising a hood in which an arm is adapted to be held, said hood having a pair of projections forming a resilient closing 55 means for said hood, the arm intended to

enter the hood being adapted to pass between said projections, said projections comprising material forced out of the material from which the hood is formed.

4. A hair curler having closure means 60 comprising a hood in which an arm is adapted to be held, said hood having a pair of projections between which the arm intended to enter the hood is adapted to pass, said projections forming a resilient closing 65 means for said hood.

5. An article of the class described, comprising a pair of arms removably connected at one of their ends, one of said arms being provided with a hood into which the other arm is movable, said hood being provided with a pair of coöperating resilient projections between which said last mentioned arm is moved in entering into the 70 hood.

6. An article of the class described comprising a hair curler having a pair of resilient arms, one of said arms being provided at its end with a hood into which the end of the other arm is movable, said hood 80 being formed from a lateral extension on the end of the arm on which it is formed, said extension being bent to overlie the end of said arm and a pair of contacting, movable projections closing the entrance to said 85 hood.

7. In a hair curler, an arm having closure means comprising a lateral extension bent to overlie the end of said arm and form a hood, and a pair of movable contacting projections resiliently closing the entrance to said hood.

8. A hair curler having an arm, a strip of material extending transversely across said arm at the end thereof, and locking means 95 comprising a projection on said strip, and a projection on the arm coöperating with the projection on the strip.

9. A hair curler having a pair of arms, a hood at the end of one of the arms into 100 which the end of the other arm is adapted to be passed, and a pair of separable, resiliently mounted projections normally closing the entrance to the hood and between which the arm adapted to enter the hood is 105 passed.

Signed at the city, county and State of New York, this 9th day of March, 1920.

HARRY RADZINSKY.
